UNITED STATES PATENT OFFICE.

JOSEPH F. HEWITT AND CHARLES W. SPATIG, OF ALLEGHENY, PENNSYLVANIA.

ELECTRIC HEATER.

SPECIFICATION forming part of Letters Patent No. 729,862, dated June 2, 1903.

Application filed December 30, 1901. Serial No. 87,730. (No model.)

To all whom it may concern:

Be it known that we, JOSEPH F. HEWITT and CHARLES W. SPATIG, citizens of the United States, residing at Allegheny, in the county 5 of Allegheny and State of Pennsylvania, have invented a new and useful Improvement in Electric Heaters, of which improvement the following is a specification.

This invention relates to certain new and 10 useful improvements in electric heaters, and relates particularly to such class of heating devices as are employed for heating beds and also for various heating purposes in any instance where the same may be required.

15 The invention has for its object to construct a device of this class having an insulated core wrapped with wire, the convolutions of the wire being wrapped so as not to come in contact with each other, or a coil may 20 be employed instead of the core, and the coil or core has connected thereto a plug for attachment to the ordinary incandescent-lamp socket.

Briefly described, therefore, the invention 25 comprises an apparatus consisting of a metallic case for electric heating purposes. This case contains a receptacle which is insulated with mica and other material. In this receptacle is placed a resistance-core which heats 30 the case. A lid carrying an insulating-tube covers the coil, and a flexible lamp-cord passes through the tube and is connected to the coil. The other end of the cord is connected to a plug adapted for engagement in an incandescent-lamp socket, and all of this construction 35 will be hereinafter more specifically described, and then particularly pointed out in the claim.

In describing the invention in detail reference will be had to the accompanying drawings, forming a part of this specification, and wherein like numerals of reference will be employed for designating like parts throughout the several views of the drawings, in 45 which—

Figure 1 is a perspective view of our improved electric heater. Fig. 2 is a central longitudinal section thereof. Fig. 3 is a transverse vertical sectional view taken on the line 50 3 3 of Fig. 2. Fig. 4 is a side elevation of a modified form of device. Fig. 5 is a transverse

vertical sectional view of the same. Fig. 6 is a modified form of heating-coil.

To put our invention into practice, we provide a casing or receptacle 1, which may be 55 made of any suitable material readily conductive to heat and may be made in any approved or desired form, a practical form being that shown in the illustration, in which the receptacle is shown substantially oblong 60 or rectangular in shape with rounded ends. This receptacle is provided with interior partitions 2, which form a box to receive the iron core or heating-coil 3. This latter is insulated with asbestos 4 or other suitable material 65 which prevents the wire or core from coming in contact with the metal and has the feed-wire 5 connected thereto. In practice it is the intention to connect this feed-wire direct to an ordinary plug for engagement in the 70 ordinary incandescent-lamp sockets. The core or coil is covered by means of a lid 6, hinged or slidably connected to the upper face of the receptacle and having an insulated tube or sleeve 6', through which the feed-wire 75 is passed. The space within the receptacle surrounding the heating coil or core may be filled with water, as shown, or this space may be left vacant, and the air contained therein becoming heated will serve the same 80 purpose as the heated water. It is preferable, though, to provide the receptacle with an inlet 7, so that water may be placed therein when desired, and this inlet may be normally sealed by means of a screw-cap 8. 85

In Figs. 4 and 5, we show a modified form of construction, in which the receptacle 1' is in the form of an inverted T, and the heating-core, as shown, is hollow to allow the water to pass through, this core being placed with 90 in the inclosing walls 2', as in the preferred form of construction. This form of construction may also be provided with an inlet 7', so as to permit the filling of the receptacle with water. This hollow core will materially assist in the heating when water is used.

In Fig. 6 we show another modification, in which we have a series of pipes connected together and connected to a hollow core. These pipes 8' are connected to the core 9', so that 100 water may circulate therethrough.

In the practice of the invention it will be

observed that various changes may be made in the details of construction without departing from the general spirit of our invention.

Having fully described our invention, what we claim as new, and desire to secure by Letters Patent, is—

An electric heater comprising a receptacle having partitions therein intermediate the ends and sides of the receptacle, said partitions extending from the bottom to the top of the receptacle, the top of the receptacle having an opening therein registering with the portion of the receptacle inclosed by said partitions, a heating-coil wrapped with as-

bestos arranged within said partitions, a lid 15 on the top of the receptacle extending over said coil, an insulated tube extending through the lid for the reception of the feed-wire, and an inlet in the receptacle.

In testimony whereof we have hereunto signed our names in the presence of two subscribing witnesses.

JOSEPH F. HEWITT.
CHAS. W. SPATIG.
